UNITED STATES PATENT OFFICE.

MARK BARR, OF BROADHEATH, ENGLAND, ASSIGNOR TO THE LINOTYPE COMPANY, LTD., OF LONDON, ENGLAND.

PANTOGRAPH.

SPECIFICATION forming part of Letters Patent No. 723,978, dated March 31, 1903.

Application filed August 14, 1899. Serial No. 727,137. (No model.)

To all whom it may concern:

Be it known that I, MARK BARR, of Broadheath, in the county of Chester, England, have invented certain new and useful Improvements in Pantographs; and I do hereby declare the following to be a full, clear, and exact description of the invention, such as will enable others skilled in the art to which it appertains to make and use the same.

10 The present invention relates to improvements in pantographs and is specially applicable to pantograph engraving-machines.

Referring to the accompanying figures, which are to be taken as part of this specification and read therewith, Figure 1 is a plan; Fig. 2, a front elevation corresponding therewith; Figs. 3 and 4, details on the same scale;

15 Fig. 5, a detailed front elevation, on an enlarged scale, of the free end of the rigid bar and its support; Fig. 6, a detail rear elevation of the same, and Fig. 7 a plan corresponding with Fig. 5.

a is the base-plate, and *b* is a bridge-piece standing upon the base-plate *a*, to which it is 20 securely bolted, as shown at *c c*. It serves principally to furnish a vertical bearing *d* for the spindle *e*. The bottom end of this spindle turns in a foot-bearing *f*, which is carried by a stirrup *g*, made fast to the under side of the base-plate *a*. The top of the spindle *e* stands up above the bearing *d* for some distance for a purpose which is explained farther on.

h is a lever having its fulcrum in the spindle *e*. It is pivoted by its opposite end to the respective end of a link *i* at *z*. The other end of this link *i* is pivoted on an offset *j*, projecting from one end of a swinging bar *k*. This bar *k* is straight and rigid throughout 30 its length. Its opposite end is supported by an antifriction-roller device *l l'*, &c., which is carried by a horizontal bracket *m*, springing from a boss *n*, which rests upon the base-plate *a* and turns about the spindle *e*. *o* is 35 an arm turning by one end about the said spindle. Its outer end is not connected to any member of the pantograph.

p is a link pivoted by its respective ends to the arm *o* and to the link *i* on the axes *z'* 40 *z*. This link *p* is always parallel with the lever *h* from every point of view.

The lever *h*, the bar *k*, the arm *o*, and the links *i* and *p* together constitute the pantograph of the present invention, and the spindle *e* is the center on and about which it 55 works. The united weight of the parts *h*, *k*, *o*, *i*, and *p* is supported by tie-rods *q q'*, stretched from the collars *q' q'*, loose upon the top of the spindle *e* between two collars *q'' q''*, fast thereon, to an eye *q''* upon the lever 60 *h*, close to the outer end of it, and to a post *q''*, standing up from the outer end of the arm *o*, as shown in Fig. 2. The tie-rods *q q'* and the upstanding top of the spindle *e* are not included in Fig. 1.

65 The link *i* is adjustable in respect of its length in the same way as the lever *h* and the link *p*, as indicated at *i'*. The pivot-blocks *p'' p''* of the link *p* are adjustable lengthwise of the arm *o* and the link *i*, respectively, by 70 means of screws *o' i'*, turning in slots *o'' i''* without longitudinal advance and about axes alined with the said arm and link, respectively.

r is the tracer. It is carried by the offset *j*, with its axis coincident with the pivotal connection between the link *i* and that offset.

75 *s* is the quill that receives the engraving-tool. It revolves in a block *s'*, adjustable in a slot *s''*, lengthwise of the link. The block *s'* stands on the same side of the swinging 80 bar *k* as does the offset *j*, and the axes of the tracer *r*, of the quill *s*, and of the spindle *e* are always alined with each other. The distance from the pantograph center *e* to the axis *z'*, that from the said axis *z'* to the axis of the 85 quill, and that from the axis *z* to the axis *z''* are always equal. The adjustability of each is for variations in the ratio of reduction.

a' is the table for the pattern over which the tracer *r* is moved, and *a''* is the table for 90 the work.

The swinging bar *k* is X-shaped in cross-section, the four webs being of equal dimensions and the four internal angles right angles. Two of the webs, *k' k'*, are vertical and two, 95 *k'' k''*, horizontal. The engraving or other tool is held to the bar *k* by a device through which the said bar can slide to and fro in the direction of its length. The said device includes means by which it can be set up to the respective sides of the said bar, so as to bear 100 upon it properly.

$s^3 s^4$ are two lugs fast to the block s' , already described, and from which they project at about a right angle with each other toward the bar k and as far as its opposite side, as shown in Fig. 1.

s^5 is a horizontal bar pivoted midway of its length on the lug s^3 by a vertical pivot s^{11} .

s^6 is a vertical pivot in one end of the bar s^5 and carrying a horizontal roller s^7 on each side of the adjacent horizontal web k^2 . s^8 is a similar pivot at the other end of the same bar, carrying two rollers s^9 likewise. The rollers $s^7 s^9$ are to bear against one side of the vertical webs $k' k'$ of the bar k , while the rollers $s^8 s^8$ are to bear against the opposite side of the same webs.

s^{10} (see Fig. 4) is a flange on the bar s^5 , and s^{12} is a set-screw working through it against the lug s^3 to set the two pairs of rollers $s^7 s^7$ and $s^8 s^8$ up to the bar k .

s^{13} is a second horizontal bar, pivoted at one end on the lug s^4 by a vertical pivot s^{14} . s^{15} is a vertical pivot in the opposite end of the bar s^{13} and carrying a horizontal roller s^{16} on each side of the adjacent horizontal web k^2 , to bear against the same side of the vertical webs $k' k'$ as the two rollers s^7 , above described. Thus the two outer pairs of rollers $s^7 s^7$ and $s^{16} s^{16}$ bear against one side of the bar k , while the intermediate pair $s^9 s^9$ bears against the opposite side.

s^{17} is a set-screw working through a flange on the bar s^{13} and against the lug s^4 , between the pivots s^{14} and s^{15} , to set the pair of rollers $s^{16} s^{16}$ up to the respective webs $k' k'$ in the same way as the set-screw s^{12} sets up the pair $s^7 s^7$.

The antifriction-roller device $l l'$, &c., already mentioned as constituting a supporting device for the end of the bar k opposite to the tracer r and through which the said end can move freely to and fro in the direction of its length is of the same type as that just described for holding the tool-holding block s' and bar k together. The rollers of it, however, bear upon the horizontal webs $k^2 k^2$ of the bar k , as well as upon the vertical webs $k' k'$.

l^1 is a bar pivoted midway of its length on a horizontal pivot l^5 , carried by the end of the bracket m , already described.

l^2 is a horizontal pivot in one end of the bar l^1 and carrying a vertical roller l on each side of the top web k' . l^3 is a similar pivot in the other end of the bar l^1 and likewise carrying a vertical roller l' on each side of the bottom web k' . The rollers $l l'$ are to bear down upon the top and the rollers $l' l'$ up against the bottom faces of the horizontal webs $k^2 k^2$.

m' is a set-screw working through a projection m^2 on the bracket m and against the bar l^1 , between the pivots l^3 and l^5 , to set the two pairs of rollers $l l$ and $l' l'$ up to the respective faces of the horizontal webs $k^2 k^2$.

l^{10} is a second and horizontal bar pivoted midway of its length on a vertical pivot l^{25} , carried by a lug l^{26} , fast on the bracket m .

l^9 is a vertical pivot in one end of the bar l^{10} and carrying a horizontal roller l^8 on each side of the said bar l^{10} . l^{12} is a similar pivot at the other end of the same bar, carrying two rollers $l^{11} l^{11}$ likewise. The rollers $l^8 l^8$ are to bear against one side of the vertical webs $k' k'$, and the rollers $l^{11} l^{11}$ are to bear against the opposite sides of the same webs.

m^3 is a set-screw working through a projection m^4 on the bracket m and against the bar l^{10} , between the pivots l^{25} and l^{12} , to set the two pairs of rollers $l^8 l^8 l^{11} l^{11}$ up to the respective webs $k' k'$.

l^{14} is a third bar pivoted at one end on a lug l^{16} on the bracket m (see Fig. 3) by a pivot-pin l^{27} , which is held fast to the said lug l^{16} . l^{15} is a vertical pivot in the opposite end of bar l^{14} and carrying a horizontal roller l^{17} on each side of the said bar to bear against the same side of the vertical webs $k' k'$ as the pair of rollers $l^8 l^8$, already described.

m^5 (see Fig. 3) is a set-screw working through a projection m^6 , fast on the pivot-pin l^{27} and against a flange m^7 on the bar l^{14} , between the pivots l^{15} and l^{27} , to set the rollers $l^{17} l^{17}$ up to the respective webs $k' k'$.

l^{18} is a fourth bar, pivoted at one end on a horizontal pivot l^{19} , fast to the bracket m . l^{20} is a horizontal pivot in the opposite end of the said bar l^{18} and carrying a vertical roller l^{21} on each side thereof to bear against bottom faces of the horizontal webs $k^2 k^2$, as do the rollers $l' l'$. m^8 (see Figs. 1 and 2) is a set-screw working through a projection m^9 , fast on the bracket m and against the said bar l^{18} , between the pivots $l^{19} l^{20}$, to set the pair of rollers $l^{21} l^{21}$ up to the horizontal webs $k^2 k^2$.

c^3 is a rest fast upon one corner of the table c' to receive the small diameter r' of the tracer when the latter has to be changed.

The mechanism for rotating the quill s is as follows:

y is the first motion-pulley and loose upon the spindle e . It is driven by a cord y' .

y^2 is a second pulley fast to the pulley y .

y^3 is a pulley connected by a sleeve y^4 to a pulley y^5 . The sleeve is carried by a vertical post y^6 , fast to the pivot-block y^3 of the link p .

y^7 is the driving-cord around the pulleys $y^2 y^3$, and y^8 the one around the pulley y^5 and the quill-pulley y^9 .

Heretofore the arm o has been of the same length as the link i , and the link p has been connected to the outer ends of the said link i and arm o . According to the first part of the present invention the length of the arm o is reduced to about one-third and the connections of the link p to the said arm and link i placed correspondingly nearer to the lever h , with the practical advantage that during the time the operator is at work his access to his work is not interfered with by any of the members of the pantograph system. The adjacent ends of the swinging bar k and the link i are held together by being pivoted about the axis of the tracer r . Consequently the tracer makes every other mem-

ber of the pantograph move with it. Especially does it push the bar *k* before it through the device that holds the tool-block *s'* to it and the device that supports the opposite end of it, instead of leaving the end of the said bar behind it to be in the operator's way by overhanging the table *a'*. The block *s'*, that carries the engraving-tool quill, cannot bind in the slot *s²*, because the two links *h* and *p* are of the same length and must be always parallel with each other.

I claim—

The hereinbefore-described combination in a pantograph, of rigid bar having the tracer fast to one end thereof and holding the tool and tracer alined with the center of the instrument; supporting device on which the other end of the said rod can move freely to and fro in the direction of its length; lever

pivoted by one end about the said center; *20* short arm pivoted about the said center; link pivoted by one end on the outer end of the said lever and having its opposite end pivoted upon the tracer; link to carry the tool-holding block and pivoted by its ends to the *25* short arm and link respectively near the said lever and always parallel with the latter; and tool-holding block held to the rigid bar above mentioned by a device permitting the said bar to slide to and fro in the direction of its *30* length.

In testimony that I claim the foregoing as my invention I have signed my name in presence of two subscribing witnesses.

MARK BARR.
